UNITED STATES PATENT OFFICE.

EDWIN F. GUTH, OF ST. LOUIS, MISSOURI.

LIGHTING UNIT.

1,294,900.

Specification of Letters Patent. Patented Feb. 18, 1919.

Application filed August 18, 1917. Serial No. 186,861.

To all whom it may concern:

Be it known that I, EDWIN F. GUTH, a citizen of the United States of America, residing at the city of St. Louis, State of Missouri, United States of America, have invented a certain new and useful Lighting Unit, of which the following is such a full, clear, and exact description as will enable any one skilled in the art to which it appertains to make and use the same, reference being had to the accompanying drawings, forming part of this specification.

My invention relates to a light controlling device embodying means for reflecting and diffusing rays of light emanating from a source of illumination, and means for controlling said rays to efficiently utilize them for the illumination of the space where light is required for useful purposes, which is sometimes referred to as the "working plane." A further object of the invention is to produce a light controlling device of simple and inexpensive construction, which will achieve the purposes above outlined, and which will also permit a portion of the light to pass toward the ceiling and sufficiently illuminate it to avoid the formation of shadows thereon.

A light controlling device or shield embodying my invention is illustrated in the accompanying drawing. In the preferred form of construction the shield is made of glass in one piece, the upper portion 1 and the lower portion 3 being of translucent glass, and the central portion 2 being transparent and provided with prismatic surfaces as shown. The lip 5 provides convenient means for attachment of a holder or other supporting or suspending device. The lamp 4 is preferably positioned below the plane of the lower portion of the prismatic section and preferably within the translucent portion 3. Laterally and downwardly directed rays of light from the source pass through the translucent portion 3 and are diffused thereby, whereas upwardly directed rays of light strike the upper portion 1 of the shield, which, while translucent, has its under-surface polished or otherwise treated whereby much of the light will be reflected, and the position of this surface is such with reference to the position of the surface of the prismatic portion 2 that the reflected rays are directed to the prismatic portion. The prisms are preferably arranged to reflect these reflected rays outwardly, that is

to say, increase their inclination with respect to a horizontal plane passing through the light source, and thus increase the total illumination in the area to which they are directed, which area is less strongly illuminated by the light passing through portion 3 than is the area immediately beneath and adjacent to said portion. I thus effect a comparatively even distribution of light over an area of the working plane which is larger than the area of even distribution which would exist if none of the upwardly directed rays of light from the source were directed back to the working plane, or than if these rays were not directed outwardly at a greater angle than their angle of reflection from the reflector above the light.

In addition to their function of controlling the direction to the reflected rays, the prisms in the portion 2 of the shield prevent images of the lamp filament, appearing in the reflector 1, from being visible.

As previously indicated, I prefer to employ such material and reflecting surface for the portion 1 of the shield as will permit some light to pass directly through this portion to the ceiling, but preferably also limiting the amount of light to the ceiling to sufficient to prevent the formation of shadows of the fixture itself, or of other fixtures thereon, in order that the major portion of the light may be directed in the shortest path possible to the useful or working plane, and the useful efficiency of the unit be made as high as possible. For example, the portions 1 and 3 may be made of what is known in the trade as "enameled" glass and the portion 1 may be provided with a heavier coating of "enamel" than the portion 3.

Modifications in structure and arrangement are possible, and it will be understood that I do not intend that the scope of my invention be limited to the preferred form herein described.

Having fully described my invention, what I claim as new and desire to secure by Letters Patent of the United States is:

1. The combination with a source of light, of a translucent shield on one side of a plane of the light, light reflecting means on the opposite side of said plane, and refracting means for altering the direction of the reflected rays; said reflecting and refracting means being positioned to give refracted rays a general direction corresponding to

that of the direct rays through the translucent shield.

2. In combination, a light shield having a prismatic portion, and a source of light within the shield, the prismatic portion being above the source of light so positioned relative thereto that the direct rays therefrom do not impinge upon its inner surface, and means to reflect light from the source to

10 the prismatic portion.

3. In combination, a light controlling shield having a prismatic portion and a translucent portion below the prismatic portion, a source of light within the translucent portion, and means for directing rays of light from said source to the prismatic portion.

4. The combination with a source of light, of a light controlling shield inclosing said source, said shield having a prismatic central portion and translucent upper and lower portions.

5. The combination with a source of light, of a light controlling shield inclosing said source, said shield having a prismatic central portion and translucent upper and lower portions, the upper portion being positioned to reflect light from the source to the prismatic portion.

6. In combination, a unitary glass shield 30 having its upper and lower portions formed of translucent glass and its central portion of prismatic glass, and a source of light within the shield, the upper portion of the shield being positioned and adapted to reflect light to the prismatic portion.

7. In combination, a unitary glass shield having its upper and lower portions formed of translucent glass and its central portion of prismatic glass, and a source of light in 40 the lower portion, the upper portion of the shield being positioned and adapted to reflect light to the prismatic portion.

8. In combination, a unitary glass shield having its upper and lower portions formed 45 of translucent glass and its central portion of prismatic glass, a source of light in the lower portion, the upper portion of the shield being positioned and adapted to reflect light to the prismatic portion, and the 50 prismatic portion being adapted to change the direction of the reflected rays to increase their angle with respect to a horizontal plane through the source of light.

In testimony whereof I have hereunto set 55 my hand and affixed my seal.

EDWIN F. GUTH.
